FEED ROLLER

Louis W. Roselius, New York, and Anthony F. Peropat, Brooklyn, N. Y., assignors to S. & S. Corrugated Paper Machinery Co., Inc., Brooklyn, N. Y., a corporation of New York

Application January 16, 1937, Serial No. 120,886

3 Claims. (Cl. 271—2.3)

This invention relates to feed rollers for sheet material, and more particularly relates to feed rollers for printer and printer-slotted machines used in the manufacture of corrugated and fibre board containers.

Corrugated and fibre board containers are manufactured from sheet material automatically cut to size and shape, and scored or creased at predetermined lines so that the blank may be folded up and pasted into final form. The cutting, shaping and creasing operations are generally performed prior to printing operations upon the blank. The printing may be multi-colored or of a single color. Accurate registration of successive printing operations upon the blank is essential for quality work. Even a small amount of slippage or irregular feeding of the corrugated sheet will cause poor registration of the printing.

To accomplish positive feeding of the corrugated board through printer, printer-slotted machinery or the like, a pair of coating feed rolls have heretofore been employed. To predetermine the folded lines in the blank, creases or score lines are made in the corrugated board. These score lines are regions of diminished thickness. A score line parallel to the axis of the feed rolls resulted in slippage when the score line reached the position between them due to the materially reduced pressure at the region of decreased thickness in the blank. It was the general practise to adjust the rollers closer together than necessary for normal feeding so as to avoid slippage when the scored region passed between the feed rolls. The abnormal closeness of the feed rolls caused crushing of the corrugated board structure.

In accordance with the present invention, an auxiliary pair of feed rolls is located near the regular pair. Two sets of adjacent feed rolls are adjusted to an operating pressure corresponding to the normal board thickness to avoid any crushing of the corrugated board. Both sets of rolls are driven in synchronous speed relation. When a score line passes between one set of rollers, the other set of rollers continue to advance the sheet in a positive manner. No slippage occurs with this arrangement since when one set of rolls tends to slip, the other set continue the positive feeding action.

It is accordingly an object of this invention to provide novel methods of and means for feeding sheet material.

Another object of the invention is to provide novel arrangements of feed rollers for corrugated board machinery.

A further object of the invention is to provide novel positive feeding means for corrugated blanks containing score lines.

These and other objects of the invention will become apparent in the following description taken in connection with the drawing, in which:

Figure 1 is a schematic illustration of a single pair of feed rollers operating on corrugated board.

Figure 2 is a schematic diagram of the principle of adjacent feed roller pairs as used in the invention.

Figure 3 is an end view of a preferred arrangement for synchronously driving pairs of feed rollers for a printer machine.

Figure 1 is a diagrammatic view of the prior art feed roll mechanism for advancing the corrugated sheet 10. This arrangement essentially comprises two opposed pressure or feed rollers 11 and 12 of equal diameter positively geared to rotate at identical speeds.

Rollers 11 and 12 are driven by shafts 13 and 14 respectively. The distance between shafts 13 and 14 is adjustable to control the pressure of the rollers 11 and 12 upon the blank 10. There is schematically illustrated one form of pressure controlling means at 9, it being understood that other methods for effecting this adjustment may be used.

If the pressure is adjusted so that corrugated sheet 10 is not normally crushed, feeding difficulties are encountered due to slippage at score lines such as 15 arranged in blank 10 parallel to the axis of rollers 11 and 12. The sudden decrease in cross-section of corrugated board 10 affects the positive gripping action on the sheet by rollers 11—12 so as to cause slippage or otherwise uneven feeding of sheet 10. The printing cylinder containing the type must accurately register upon blank 10, particularly in multi-color printing machines. A pair of rollers such as 11—12 is generally provided at the input and outlet of the printing units to perform the feeding operation. Slippage at one pair of rollers may cause buckling or wrong positioning of the sheet between such relatively widely separated single pairs of feeding rollers to interfere with the printing registration on the sheet.

Figure 2 diagrammatically illustrates the improved feeding mechanism as practised by the present invention. Two closely situated pairs of feed rollers 16—17 and 18—19 are arranged to operate upon the advancing corrugated blank 10. The transverse score line 15 in sheet 10 is shown situated between roller pair 16—17 corresponding

to rollers 11-12 of Figure 1. The pair of rollers 18-19 preferably similar to the pair 16-17 are located adjacent thereto and on either side thereof. The two pairs of rollers may be considered as a roller group replacing the single pair of rollers 11-12 heretofore used.

The roller pairs 16-17 and 18-19 are secured respectively to shafts 20, 21, 22 and 23 rotated in synchronous relation to positively feed sheet 10 in a predetermined direction. The distance between shafts 20-21 and shafts 22-23 may be adjusted by means well known in the art to cause a predetermined gripping pressure upon blank 10 by both roller sets. The gripping pressure of the rollers is such as to avoid crushing of the corrugated sheet 10 and yet permit a positive feeding action.

It is preferable to operate the pressure or distance adjustment of both pairs of adjacent rollers simultaneously and from a unitary control so as to insure uniform action thereof. A common control arm 24 connected to the upper rollers 16-18 for lifting or lowering them in unison with respect to the stationary axes of the lower rollers 17 and 19 is schematically illustrated. It is to be understood that the unitary control may be used for the lower rollers instead of or together with the upper ones. Any of the several means well known in the art for variably separating a single pair of rollers may here be combined with the common control arm 24 for the simultaneous adjustment. Thus there is illustrated in Figure 2 schematically mechanism for vertically adjusting the position of the upper rollers 16 and 18 with respect to the corresponding rollers 17 and 19. The common yoke 24 connects the upper rollers 16 and 18 at their respective shafts 20 and 22 so that any movement imparted to one roller is similarly imparted to the other roller. An arm 42 extends from the yoke 24 through a portion of the frame 40. A nut 41 coacts with a threaded portion of the rod 42 to variably position the control arm 24. A spring 43 mechanically biases the yoke 24 downwardly with respect to the frame 40, as shown. The rollers 16 and 18 are accordingly in a suitable operating position and their distance of separation from the lower rollers is determined by a predetermined adjustment of the nut 41 upon the threaded portion 42, as will now be evident.

The auxiliary roller pair 18-19 being located adjacent to roller pair 16-17 maintains a positive grip upon blank 10 while roller pair 16-17 is engaging the scored region 15 of blank 10. The blank 10 is accordingly continuously advanced without interference since the roller pair 18-19 acts independently of the other pair in feeding the sheet. In a similar manner when the score line 15 has reached the position between rollers 18-19, the first roller pair 16-17 will have a positive grip upon sheet 10 to continue its steady progress through the apparatus. No slippage, buckling or uneven feeding of the corrugated blank 10 occurs by using the dual pair of feed rollers.

Figure 3 is an end view of a machine for operating upon corrugated board sheet 10 employing the positive feeding roller groups of the present invention. The primary utility of this invention is for machines for printing upon the blank, particularly for multi-color printing where accurate registration is necessary. A printing drum is illustrated at 30 having a presser roller 31 cooperating with drum 30 to maintain a predetermined pressure for printing upon blank 10.

At the input and output positions of drum 30 is shown a group of rollers for positively feeding the blank.

The feed rollers 16 to 19, arranged in two adjacent pairs in accordance with the illustration of Figure 2, are driven by respective gears 25 to 28 attached to their shafts 20 to 23 respectively. Gear 25 meshes with gear 26 and gear 27 meshes with gear 28. The lower gears 26 and 28 are shown meshing with a driver gear 29 which is connected to the power gears of the machine. By using gears 25 to 28 of the same diameter, the peripheral speeds of the equi-diameter rollers 16 to 19 will be synchronously maintained. The feed roller groups on opposite sides of drum 30 are similar in construction and are rotated so as to accurately move corrugated boards 10 between drums 30 and 31 at a predetermined rate. The drive gear 29 for each group are driven at the same speed by interconnecting gears not shown but well known to those skilled in the art.

Although we have illustrated a preferred drive gear arrangement for the roller groups 16 to 19, it is to be understood that the driving arrangement for the rollers may take many different forms as practised in the art. Various compensating arrangements to accommodate the variable separation within the roller pairs for different sheet thicknesses are used for the gear drives of feed rollers. Such arrangements may be employed for the dual roller pairs 16-17 and 18-19, in conjunction with a common pressure control arm as described in connection with arm 24 of Figure 2.

It is to be understood that the feed rollers of the present invention may be used for feeding corrugated board, fiber board or any board or sheet material where regions of diminished sheet thickness, transverse to the feeding direction, occur. Since two pairs of rollers are used where a single pair were previously employed, the pressure of any particular roller upon the sheet is less and crushing of the board is avoided. Furthermore, it is also to be understood that a plurality of pairs of feed rollers may be used in any one machine; in fact, may be used to replace the prior art feed rollers applied to any machine. Thus, for example, although a single printing drum is illustrated in Figure 3 with an input and output feed roller set, it is to be understood that a machine employing multi-color type drums or other rotating members may employ the feed rollers of the present invention.

We claim:

1. Means for feeding a sheet of corrugated board material having a transverse score line comprising a first pair of coacting rollers for normally advancing said sheet, a second pair of coacting rollers normally independently capable of advancing said sheet, means for simultaneously adjusting the distance between the rollers of said pairs to accommodate different sheet thicknesses, said means comprising a yoke in which corresponding rollers of said pairs are journaled, and means for confining said yoke to movement normal to the plane of said corrugated board, said rollers being driven at synchronous peripheral speed to positively advance said sheet irrespective of said score line reaching either pair of rollers.

2. Means for feeding a sheet of corrugated board having a transverse score line comprising a first pair of coacting rollers arranged to grip upon opposite faces of said sheet for normally advancing said sheet, a second pair of coacting

rollers normally independently capable of advancing said sheet located adjacent said first pair of rollers, and arranged to grip upon opposite faces of said sheet, means for simultaneously and substantially equally adjusting the distance between the rollers of said pairs to accommodate different sheet thicknesses, said means comprising a yoke in which corresponding rollers of said pairs are journaled, and means for confining 5 said yoke to movement normal to the plane of said corrugated board, a source of motive power, and means controlled by said source for rotating said rollers at synchronous peripheral speed to positively advance said sheet irrespective of 10 said score line reaching either pair of rollers.

15 3. In a machine for operating upon an advancing corrugated board sheet having a transverse score line, a rotatable drum, means for feeding said sheet past said drum comprising a first pair of coating rollers arranged to grip upon opposite faces of said sheet for normally advancing said sheet, and a second pair of coating rollers located adjacent said first pair of rollers and arranged to grip upon opposite faces of said sheet, 5 means for simultaneously adjusting the distance between the rollers of said pairs to accommodate different sheet thicknesses comprising a common yoke for corresponding rollers of said pairs, and means for confining said yoke 10 to vertical movement with respect to said corrugated board, a source of motive power, and means controlled by said source for rotating said rollers at synchronous peripheral speed to positively advance said sheet irrespective of said 15 score line reaching either pair of rollers.
